UNITED STATES PATENT OFFICE.

ELIAS BEACH, OF CHICAGO, ILLINOIS, ASSIGNOR TO HIMSELF AND PATRICK HUGHES, OF SAME PLACE.

MOP-WRINGER.

SPECIFICATION forming part of Letters Patent No. 509,717, dated November 28, 1893.

Application filed June 24, 1893. Serial No. 478,702. (No model.)

To all whom it may concern:

Be it known that I, ELIAS BEACH, a citizen of the United States, residing in Chicago, in the county of Cook and State of Illinois, have 5 invented a new and useful Improvement in Mop-Wringers, of which the following is a specification.

This invention relates to certain improvements in the construction of a combined 10 bucket holding frame work and mop wringing rolls, the whole constituting a strong, cheaply made and convenient apparatus for holding a bucket of water and for wringing a mop.

The nature of the invention in detail will 15 be apparent from the following specification and claims and the accompanying drawings, which form a part of this specification, and in which—

Figure 1 is a side elevation of the apparatus, showing the same in position to be carried about and lifted by the handle of the enclosed bucket. Fig. 2 is a similar view showing the mop wringing rollers lifted away to permit the insertion or removal of the 25 bucket. Fig. 3 shows a similar view with the rollers closed down together as when the mop is being wrung. Fig. 4 is a top or plan view with one of the rollers lifted to the position for permitting the mop to be put into the 30 bucket. Fig. 5 is an end view of the frame work. Fig. 6 is an enlarged view of a portion of the apparatus. Fig. 7 is a plan view of the parts shown in Fig. 6. Fig. 8 is a section on the line 8—8 of Fig. 3; and Fig. 9 is a section 35 on the line 9—9 of Fig. 4.

Like letters of reference indicate like parts throughout all the figures.

One of the objects which I have had in view is to so contrive the various parts that 40 the frame work and hinged roller supports may be constructed principally of common band or strap iron, and yet be light, strong, durable and easy to operate.

In the drawings A A are two foot pieces 45 which rest upon the floor, parallel to each other and are connected together by means of the horizontal step piece A' and the base or bottom piece A², the latter being shown in Fig. 4 and indicated in dotted lines in Figs. 1, 2 and 3.

50 These parts A, A', A² I prefer to make of hard

wood, and they give lateral support and rigidity to the entire structure. The bottom piece A² forms a support upon which the water bucket B rests when the apparatus is in use.

Secured to the foot piece A are four vertical pieces of strap or band iron C rising to about the height of an ordinary water bucket or pail. Around the upper ends of these four uprights I bend in the form of a square the band piece D, riveted to each of the uprights 60 and having its own ends riveted together as at d. (See Fig. 5.)

At the rear and near the floor I place the short strap D' extending from one of the uprights C to the other. This metal strap D' 65 gives lateral strength to the lower rear part of the structure. And at front and rear I apply the diagonal braces E E which give complete rigidity to the entire frame work. The braces E E at the rear are riveted to the 70 top band D at their upper ends, and to the short strap D' at their lower ends. The corresponding braces E E in front are riveted at their upper ends to the top band D and at their lower ends may be secured to the wooden 75 step piece 'A'. It will be seen that the structure thus far described constitutes a square hollow frame work very light, and at the same time rigid. This hollow frame work is made large enough to receive an ordinary 80 bucket B.

FF' are two rollers which may be made of any suitable material, as for example rubber if elasticity is desired, or of wood. I prefer to make them of wood. These rollers are so mounted 85 that a line passing through their axes will form an angle to the horizon, which arrangement somewhat facilitates the handling of the mop in the operation of wringing the same. Each of the rollers is mounted upon swinging arms, 90 which enable them to be thrown back away from the frame work, as shown in Fig. 2, to completely open the frame for the insertion and removal of the bucket. After the bucket is in place however, it will not be necessary for 95 the operation of the apparatus to swing back the lower roller F, which is intended therefore to normally remain in the position in which it is shown in Fig. 3, the movement for inserting and removing the mop being 100

confined to the roller F'. The roller F is journaled in the swinging arms G pivoted at g to the upper ends of the uprights C of the frame work. These arms G are extended beyond the roller and their inner ends recurved to form the extensions G'. These extensions G', when the roller is in position over the bucket, afford guides which serve to keep the edges of the mop, in the act of wringing, centrally over the bucket and thus insure the wringing of the whole mop, and also tend to prevent the mop getting into such a position that the water squeezed out of it will spill upon the floor.

15 The journal of the roller F consists of a simple rod passed through the roller from end to end if desired; or of two pins one inserted into each end of the roller. In order that the bearing for these journals may be sufficient to prevent the thin band or strap iron from being cut out by wear, I provide the extra band piece H at each side cut with a notch h, and the journals are made long enough to rest in these notches h. The pieces H are set off from the frame work to leave a space, say of an eighth of an inch or more between themselves and the top band D for a purpose presently to be explained, and they are secured in place by the pivots g at one end and at the other end by the pivots g². The roller F' is journaled in the swinging arms G² pivoted at each side to the top band D by the pivot g².

35 To afford means for raising, lowering and holding the roller F' in place, and giving the requisite pressure, I provide the foot treadle J, which I make of a piece of strap iron bent approximately into the form of the three sides of a square and extending out to the front of the apparatus as shown in the drawings. The rear ends of this strap or foot lever J I pivot at j to the rear upright C.

40 At each end of the roller F' and extending from its journals to the foot lever J is the piece K made of strap iron and pivoted at k to said lever J. It will be seen that by this arrangement the operator by putting his toe under the lever J and lifting said lever may throw the upper roller F' back or into the position in which the same is shown in Figs. 2 and 4, thus opening the apparatus for the insertion of the mop, and when said lever is brought down again, the mop being in place, any pressure desired may be applied upon the mop with the foot resting upon the lever. The piece K plays in the space between the extra strap H and the band D, being guided and steadied thereby against any lateral spring, and this guiding is the additional purpose above spoken of which the said extra strap H performs.

45 To insure steadiness of movement in swinging and to cause the roller to move truly in the swinging operation, I find it desirable to make the pivoted attachment between the piece K and the lever J, as shown in Fig. 8. A short extra piece of strap iron K' is riveted

5 to the lower end of the piece K, and the pivot k is passed through the three pieces K, J and K', which prevents any tendency for the parts to get awry in the operation of swinging the roller.

60 I had some little difficulty in getting a suitable bearing for the journals of the roller F' which would not cut out until I had contrived the form of bearing shown at Fig. 9, which consists in a thimble L passing through the arm G² and piece K, and provided exteriorly with the washer l and screw l', the latter setting into the end of the journal. The journal bears in the thimble, and as a result a firm joint and smooth bearing are produced and the cutting is avoided.

65 The crank handle M is or may be attached to the journal of the upper roller F' and is useful in turning said roller to squeeze the mop when it is desired to bring considerable pressure upon it in order to wring it quite dry.

70 In operation to insert the bucketful of water, both of the rollers are thrown back on their swinging arms into the position shown in Fig. 2. The lower roller F is then swung into place over the bucket as shown in Figs. 1, 3 and 4 when the mop may be inserted into the water and charged with the same. The roller F' is then swung in and down upon the mop, and if it be desired to remove the superfluous water the weight of the roller itself supplemented sometimes by a slight pressure of the foot upon the lever J will suffice, and in such case the mop may be pulled out through the rollers without using the crank handle M. If however it is desired to dry the mop as when the floor is to be wiped up with the dry mop, then in that case a more considerable pressure, and to any extent desired may be applied by means of the foot and by turning the crank handle the mop may be squeezed nearly dry. It will be noticed that the rollers come together with a wedging action by reason of the arrangement of the swinging arms G² and the connecting piece K, and consequently that a squeezing effect of very considerable force and power may be given to the mop.

75 When it is desired to carry the apparatus around from place to place either with or without water in the bucket, the construction and arrangements of the parts are such that the handle of the bucket may, by lifting the upper roller out of the way temporarily, be brought up between the rollers into the position shown in Fig. 1 when the operator may take hold of the bucket handle N, put his mop in the bucket and carry the whole apparatus, bucket, water and mop easily from place to place, the closed rollers operating to hold the structure upon the bucket.

80 I claim—

1. The combination in a mop wringer of the following parts; the foot pieces A A, the cross piece A', the base board A², the strap iron uprights C, the top band D, the diagonal braces E E, and the pair of rollers F F' journaled

in swinging arms, one only of said rollers being connected by straps K to the foot lever J, said shaft being pivoted upon the axle of roller F' substantially as specified.

5 2. The combination of the strap iron frame work for inclosing the bucket and a suitable base therefor, of a swinging roller, a foot lever for operating the same, and a normally stationary roller hinged to the frame work by
10 means of arms G so that it may be swung out of the way to admit the bucket, substantially as specified.

3. In a mop wringer the combination with suitable frame work for supporting the bucket, of two rollers F F' both of which are 15 journaled in swinging arms so that they may be lifted entirely away from over the bucket, and a foot lever and connection from said foot lever to one only of said rollers substantially as specified.

ELIAS BEACH.
